Primary Examiner — Angela J Lee

(74) Attorney, Agent, or Firm — LUCAS & MERCANTI,
LLP; Klaus P. Stoffel(57) **CLAIM**

The ornamental design for a vehicle taillight as shown and described.

DESCRIPTION

FIG. 1 is a front view of a vehicle taillight showing our design;

FIG. 2 is a front and left side perspective view thereof;
FIG. 3 is a left side view thereof, the right side being a mirror image; and,FIG. 4 is a front, top and left side perspective view thereof.
The features shown in halftone and bounded by broken lines
form no part of the claimed design.**1 Claim, 4 Drawing Sheets**(56)
